UNITED STATES PATENT OFFICE.

HENRY P. SINCLAIRE, OF CORNING, NEW YORK, ASSIGNOR TO H. P. SINCLAIRE & CO.,
OF CORNING, NEW YORK, A CORPORATION OF NEW YORK.

DESIGN FOR A BOTTLE.

48,765.

Specification for Design.

Patented Mar. 21, 1916.

Application filed January 27, 1916. Serial No. 74,710. Term of patent 14 years.

To all whom it may concern:

Be it known that I, HENRY P. SINCLAIRE, a citizen of the United States, residing at Corning, in the county of Steuben and State of New York, have invented a new, original, and ornamental Design for a Bottle, of which the following is a specification, reference being had to the accompanying drawing, forming part thereof, in which,

Figure 1 is a side elevation, and Fig. 2 is an end elevation of a bottle showing my new design.

I claim:

The ornamental design for a bottle, as shown.

HENRY P. SINCLAIRE.
